ROOM THERMOSTAT

Herbert J. Taylor, Aloha, Oreg., assignor to Sunne Controls Division of PECO Manufacturing Co., Inc., Portland, Oreg.

Filed Sept. 13, 1973, Ser. No. 397,016

Term of patent 14 years

Int. Cl. D10—05

U.S. Cl. D10—50

FIG. 1

FIG. 3

FIG. 2

FIG. 4

FIG. 5

FIG. 1 is a front elevational view of a room thermostat showing my new design;

FIG. 2 is a right side elevational view thereof, the left side being substantially a mirror image thereto;

FIG. 3 is a rear elevational view thereof;

FIG. 4 is a bottom plan view thereof, the top plan being substantially a mirror image thereto;

FIG. 5 is a rear elevational view of another embodiment of my new design of FIG. 1 wherein a larger break switch is used in the rear;

FIG. 6 is a bottom plan view of the FIG. 5 embodiment, the top plan being substantially a mirror image thereto.

I claim:

The ornamental design for a room thermostat, as shown and described.
